UNITED STATES PATENT OFFICE.

JOSEPH B. ROHRMAN, OF PHILADELPHIA, PENNSYLVANIA.

DESIGN FOR A PIPE-COLLAR AND FLUE-STOPPER.

SPECIFICATION forming part of Design No. 19,043, dated April 9, 1889.

Application filed February 7, 1889. Serial No. 299,058. Term of patent 3½ years.

To all whom it may concern:

Be it known that I, JOSEPH B. ROHRMAN, a citizen of the United States, residing in the city and county of Philadelphia, State of Pennsylvania, have invented and produced a new and original Design for a Pipe-Collar and Flue-Stopper, of which the following is a specification, reference being had to the accompanying drawing, forming part thereof.

10 The leading feature of my design for a pipe-collar and flue-stopper is the breast of the same, having thereon a circular row of figures whose sides are curved and converging at their inner ends, the outer end of each of the said figures being curved or rounded and of greater width than the inner end.

15 In the drawing, A designates a pipe-collar and flue-stopper, on the breast of which is a

circular row of figures, B, the sides of which are curved and converging at their inner ends, the outer end of each of the figures being curved or rounded and of greater width than the inner end. 20

I claim—

A design for a pipe-collar and flue-stopper 25 having on the breast thereof a circular row of figures having sides which are curved and converging at their inner ends, the outer end of each of said figures being rounded and of greater width than the inner end, substantially as shown and described. 30

JOSEPH B. ROHRMAN.
